UNITED STATES PATENT OFFICE

WALLACE B. WOLFF, OF CHICAGO, ILLINOIS, ASSIGNOR TO AMERICAN SLICING MACHINE COMPANY, OF CHICAGO, ILLINOIS, A CORPORATION OF NEW YORK

SLICING MACHINE

Application filed May 4, 1929. Serial No. 360,401.

My invention relates to a slicing machine of a type wherein a circular knife is employed, herein shown as motor driven. One object of the invention is to provide means for protecting the fingers of the operator from the cutting edge of the knife and, specifically, to provide means for substantially entirely shielding the cutting edge of the knife, from front and rear, when the device is not actually in use. Another object is the provision of an adjustable or movable means for shielding the cutting edge of the knife from the front, when the work supporting carriage is not in use. Another object is the provision of an extension for the work supporting member of said cutting carriage, which extension may be associated with or may be made to move unitarily with a guard or shield member for the cutting edge of the knife. Other objects will appear from time to time in the course of the specification and claims.

I illustrate my invention more or less diagrammatically in the accompanying drawings, wherein—

Figure 1 is a front elevation of my device;

Figure 2 is an enlarged section along the line 2—2 of Figure 1;

Figure 3 is a section on the line 3—3 of Figure 2;

Figure 4 is a perspective view of a guard plate;

Figure 5 is a section on the line 5—5 of Figure 1;

Figure 6 is a plan view of a guard plate illustrated in the position in which it is shown in dotted line in Figure 1;

Figure 7 is a partial rear elevation; and

Figure 8 is a front elevation with the parts in a different position.

Like parts are indicated by like symbols throughout the specification and drawings.

A indicates any suitable base member upon which is mounted the motor A¹ with the motor shaft A² and the pulley A³ about which passes the belt A⁴.

B generally indicates a rotary knife on the knife shaft B¹, associated with which is a pulley B² about which passes the belt A⁴.

The major portion of the front of the knife

is covered or protected by a normally fixed guard plate C, which includes arcuate edged portion C¹ adapted to be positioned within the forward recesses B³ of the knife. It will be observed that the axis of the knife is 55 shown in horizontal plane and is tilted slightly from perpendicularity in relation to the guard plate C, in order to bring the cutting arc of the knife into or beyond the plane of the guard plate. While I prefer to have the 60 axis of the knife horizontal my invention is not to be limited to the use of a knife having a horizontal axis.

D generally indicates a rear guard member associated with the hub D¹ in which rotates 65 the knife shaft B¹. In some circumstances it may be preferable to recess the rear of the knife, as at B⁴ in order to receive the edge or periphery D² of the guard D.

E generally indicates a gauge plate with 70 the arcuate edge E¹ generally concentric with and opposed to the cutting arc of the knife. Any means may be employed to move the gauge plate E toward and away from the plane of the knife, and, preferably, at the 75 same time laterally toward and away from the edge of the knife. Referring to the dotted line position of the gauge plate in Figure 6 I illustrate the preferred movement of the gauge plate, which is along a path 80 inclined to the cutting plane of the knife, in such fashion that the recess of the gauge plate widens the throat between gauge plate and knife in two directions. However the invention herein shown is operable with 85 gauge plates which are drawn directly back from the cutting plane.

Mounted on the gauge plate E I indicate a guard member G, which may be formed integrally with the gauge plate or may be 90 secured thereto as by the screws G¹. It is arcuate in form and includes a portion G² extending laterally toward the knife from the gauge plate and preferably forming generally to the contour of the knife. It will be 95 observed from Figure 6 that the guard member overlies or overlaps the rear of the exposed arc of the knife as to make it impossible for the finger of the operator accidentally to engage the knife edge along the cutting 100

arc. The size of the guarding member G^2 is such that it efficiently exercises its guarding function, even when the gauge plate is withdrawn to its maximum depth.

When the gauge plate is closely set, the guard portion G^2 may extend to or almost to the edge D^2 of the guard D . However there is sufficient space between knife and guard member for the slices to escape after they are cut. The tray generally indicated as H serves to receive the slices.

In order further to protect the fingers of the operator about the lower arc of the knife, whether from front or rear, I provide an additional guard member herein shown as adjustably mounted on the gauge plate. It includes the base portion J slotted as at J^1 to receive the securing screws J^2 . Projecting from it is the arcuate guard portion proper J^3 , which lies in the general plane of the knife and closely adjacent the cutting edge, in such fashion that the finger of the operator cannot engage the cutting edge.

It will be understood that any suitable meat carriage, herein generally indicated as K may be moved across the face of the gauge plate and guard plate, as on the tracks K^1 and K^2 . Referring for example to Figures 1 and 6 I may employ on the carriage K a work supporting means including the member K^3 somewhat inclined from the horizontal, the lower edge being bounded by a supporting flange or stop K^4 which serves to limit the downward sliding movement of the work supported upon the member K^3 . In the specific form of my invention herein illustrated K^4 is shown at right angles to K^3 , the two members lying in planes generally perpendicular to the cutting plane. K^6 is any suitable manual handle whereby the meat carriage may be moved along the tracks K^1 and K^2 .

In order to shield the cutting edge of the knife from the front when the device is not in operation I provide a supplemental guard member generally indicated as L , which may be of any desired form but is herein shown as bounded at one side by the arcuate edge L^1 . Herein shown as formed integrally with the member L and at right angles to it is the member L^2 which may be hinged as at L^3 to the upper edge of the member K^3 , in such fashion that the member L closely approaches the face of the gauge plate E and the cutting plane of the knife, but not sufficiently closely to interfere with the passage of the carriage. When it is desired to move the member L^2 into parallelism with the member K^3 , in order that it may serve as an extension thereof, this adjustment may be obtained as follows. The thumb nut L^4 , shown in Figure 3, normally is in such position as to exert tension upon the rod L^5 which in turn draws in upon the clamping member L^6 which is apertured as at L^7 to permit the pas-

sage therethrough of the holding pin L^8 which is pivoted as at L^9 to the member L . A relaxation of the nut L^4 permits the members L and L^2 to be moved into the dotted line position in which they are shown in Figure 1, at which time the thumb nut L^4 can again be drawn up. Note that the pin L^5 is positioned in a sleeve L^{10} which is rotatably mounted in the carriage K in order to compensate for the changes in angle of the rod L^8 . The sleeve is apertured as at L^{11} to permit the passage of the rod therethrough, and the drawing in upon the pin L^5 clamps the rod against the edges of the apertures. The ledge L^{12} of the sleeve L^{10} bears against the carriage K , to complete the clamping action and to properly position or space the adjusting mechanism.

Referring for example to Figures 1 and 8, when the carriage is in the position in which it is shown in Figure 1, the carriage being at the end of the cutting excursion, the member L masks the cutting edge of the knife. In order to mask the cutting edge of the knife when the carriage is at the opposite end of its excursion, before the cutting stroke, I provide a shield M which may be secured to or associated with the carriage K or to the work supporting member K^4 in any suitable manner. I have indicated it, however, as a separate element secured to the carriage K as at M^1 . The device includes a body portion M^2 which protects the lower portion of the cutting edge and the upward crescent shaped extension M^3 which is herein illustrated as extending almost to the top of the gauge plate E or the guard plate C . It will be realized of course that I do not wish to be limited precisely to any particular form or securing means, the essential being that I provide a guard which overlies or protects the cutting edge of the knife when the carriage is withdrawn to its initial position prior to the cutting stroke.

It will be realized that whereas I have described and shown a practical and operative device, nevertheless many changes might be made in the size, shape, number and disposition of parts without departing from the spirit of my invention. I therefore wish my description and drawings to be taken as in a broad sense illustrative and diagrammatic rather than as limiting me to my specific showing.

The use and operation of my invention are as follows:

In the employment of an electrically operated rotary knife slicing machine, the knife edge rotates at a very high rate of speed and would therefore be dangerous to a careless operator if not properly protected. The slicing machine herein described and shown reduces the hazards to a minimum. The operator is protected, on the rear side of the knife, to the degree that it is practically impossible

for involuntarily engaging the cutting edge of the knife, the cutting edge being protected from contact as by the guards G^2 and J^3 . Such portion of the knife edge as is not protected by the said two guards is housed within the frame or housing of the slicing machine and cannot be touched.

As to the front of the machine, however, it is inevitable that a certain portion or arc 10 of the knife edge must be exposed during the cutting portion since otherwise the work to be cut cannot engage the cutting edge. The lower arc of the knife is protected from the front, as well as the rear, as for example 15 by the guard J^3 , at least when the guard plate is in neutral position. In any case, as clear from Figure 1, the carriage and the tracks on which the carriage rides prevent unintended approach to the lower arc of the knife. 20 The upper arc of the knife, where the cutting actually takes place, is necessarily exposed during the cutting operation. The guard L , however, masks the cutting edge of the knife when the carriage is left at the end 25 of the tracks K^1 K^2 , in the position in which it reaches at the end of a cutting excursion. When the gauge plate is in neutral, as shown in the full line position in Figure 6, the edges mask from front as well as rear, regardless 30 of the position of the carriage. However, the operator may wish to leave the gauge plate in adjusted position, for example in the dotted line position of Figure 6, as when he interrupts temporarily the cutting operation. In such case he may protect his cutting 35 edge by merely leaving the carriage at the end of its excursion, in the position in which it is shown in Figures 1 and 6. When in such position the guard plate L on the carriage masks the cutting edge of the knife and the device may safely be left, and no opportunity is given for an unintended approach of the fingers to the cutting edge.

In the form of carriage herein shown I 40 find it extremely desirable to provide an extension to the supporting member K^3 . Such a support is of value as providing a supporting surface more extended than the one normal to the member K^3 , as when it is desired 45 to decrust bread or derind bacon or cut bacon or other substances in larger masses than usual. For example, when my machine is employed in the English market, the size of the bacon is considerably larger than the size 50 which is commonly sold in the United States and the use of the extension L^2 , which might not be necessary for cutting bacon in the United States, becomes important in cutting the larger pieces of bacon sold in the English 55 market.

Note that I have so proportioned the parts that when the member L^2 is in the dotted line position in Figure 1 the member L still covers substantially all of the cutting edge, 60 or leaves uncovered only a very small arc

at the top of the cutting edge. This small arc, however, is protected by the outward extension of the member L^2 which makes it difficult and in the highest degree unlikely, for the operator to approach his fingers to the restricted cutting edge left uncovered. 70

Note also that when the member L^2 is in the full line position, as shown in Figure 1 it exerts this additional masking effect. Thus, when the carriage is at the initial position, to the left of the track shown in Figure 1, the operator may freely grasp the handle K^6 of the carriage or the edge of the portion K^3 of the carriage. If he moves his hand along the edge of the portion K^3 toward the cutting edge of the knife he engages not only the edge K^{20} , as shown in Figure 6 but also the upstanding edge of the member L^2 , which serves the double function of actually limiting the movement of the operator's hand toward the cutting edge and of giving warning, by touch, that the cutting edge is being approached. 80

Referring to the position of the carriage in Figures 1 and 8, note that the element L protects the cutting edge when the carriage is at one extremity of its movement and the member M protects the cutting edge when the carriage is at the other extremity of its movement, prior to the cutting excursion. The knife edge being shielded when the carriage is at either end of its stroke, the edge is exposed only intermediate the stroke. If, as in the form shown in the present drawings, the member M is formed separately from the V-trough K^3 , its face lies preferably in a plane identical with or slightly to the rear of and closely adjacent to the plane of the edges of the V-trough K^3 which must closely approach the cutting plane of the knife. It is also important that when the device is in the position shown in Figure 1 the lower or body portion M^3 of the guard M shall not project sufficiently to the right to strike an operator or passerby. I may form 90 the guard of any suitable material and may for example use thin sheet metal. 95

In the use of the device, if the gauge plate is in neutral position, of course the cutting edge of the knife is protected. If the gauge plate is withdrawn from the cutting edge of the knife, the cutting edge is protected when the carriage is left at either limit of its excursion. The cutting edge is also substantially 100 protected by the carriage structure itself at some intermediate point on its excursion. In such case the cutting edge is to a degree exposed, but it is so far masked by the intervening position of the carriage that accident 105 and contact therewith is unlikely. In other words the combination of guards I disclose herein provides a very substantial protection for the cutting edge, as complete and continuous protection as it is possible to give the 110 115 120 125 130

cutting edge and still leave it free to perform its cutting function.

I claim:

1. In association with a slicing machine including a rotary knife and means for rotating it, a work supporting member and means for guiding it for movement past the cutting edge of the knife, said work supporting member including a plurality of work engaging elements in angular relation, and an extension for one of said work engaging elements, pivoted thereto.

2. In association with a slicing machine including a rotary knife and means for rotating it, a work supporting member and means for guiding it for movement past the cutting edge of the knife, said work supporting member including a plurality of work engaging elements in angular relation, and an extension for one of said work engaging elements, and means for positioning it selectively in the general plane of said element, and in a plane inclined thereto.

3. In association with a slicing machine including a rotary knife and means for rotating it, a work supporting means and means for guiding it past the cutting edge of the knife and an extension pivoted to one edge of said work supporting member for rotation about an axis generally perpendicular to the path of the work supporting means.

4. In association with a slicing machine including a rotary knife and means for rotating it, a work supporting means and means for guiding it past the cutting edge of the knife and an extension pivoted to one edge of said work supporting member, and a guard member, associated with said extension and adapted to move unitarily therewith, said guard member being adapted to overlie the cutting edge of the knife when the work supporting member is at a predetermined position adjacent the limit of its movement past the cutting edge of the knife.

5. In association with a slicing machine including a rotary knife and means for rotating it, a work supporting means and means for guiding it past the cutting edge of the knife and an extension pivoted to one edge of said work supporting member, and a guard member, associated with said extension and adapted to move unitarily therewith, said guard member being adapted to overlie the cutting edge of the knife when the work supporting member is at a predetermined position adjacent the limit of its movement past the cutting edge of the knife, and means for securing the extension and guard member in adjusted position.

6. In association with a slicing machine including a rotary knife and means for rotating it, a work supporting means and means for guiding it past the cutting edge of the knife and an extension pivoted to one edge of said work supporting member, said ex-

tension being adapted, when in one position, to extend the available supporting area of the work supporting means, and being adapted, when in another position, to serve as a guard to prevent the approach of the finger of the operator to the cutting edge of the knife.

7. In association with a slicing machine including a rotary knife and means for rotating it, a work supporting member and means for guiding it past the cutting edge of the knife, and a unitary element pivoted thereto, including a member adapted to serve as an extension for the work supporting member when in one position and adapted to serve, when in another position, as a guard to prevent the approach of the hand of the operator, and an additional guard member adapted to mask the cutting arc of the knife when the work supporting member is moved past the cutting arc of the knife.

8. In association with a slicing machine including a rotary knife and means for rotating it, a work supporting member and means for guiding it past the cutting edge of the knife, said work supporting member including a plurality of work supporting elements lying in planes generally perpendicular to the cutting plane of the knife, said elements being at an angle in relation to each other, and an extension pivoted to the outer edge of one of said elements for rotation about an axis generally perpendicular to the path of movement of the work supporting member.

Signed at Chicago, county of Cook and State of Illinois, this 19th day of April, 1929:

WALLACE B. WOLFFE.
